TUBING BLEEDER AND JAR

William H. Stigall, Taft, Calif.

Application February 26, 1937, Serial No. 128,002

2 Claims. (Cl. 103—221)

This invention appertains to new and useful improvements in tubing bleeders and jars.

The principal object of the present invention is to provide a device which will eliminate the pulling of wet tubing strings because of the positive action of the bleeder.

Another important object of the invention is to provide a combination device involving a jar mechanism adapted to free the pump mechanism or other parts in the event of sanding up of the well.

Other important objects and advantages of the invention will become apparent to the reader of the following specification.

15 In the drawings:—

Figure 1 represents a side elevational view of the apparatus.

Figure 2 is a fragmentary longitudinal sectional view of the structure.

20 Figure 2a is a fragmentary side elevational view of the lower portion of the mechanism with parts in section.

Figure 3 is a cross section on the line 3—3 of Figure 1.

25 Figure 4 is a fragmentary longitudinal sectional view through the locking device and jar.

Referring to the drawings wherein like numerals designate like parts, it can be seen in Figure 1 that numeral 5 represents an upper socket structure having the tubing connecting nipple extension 6 for connection of an upper section of well tubing, not shown, thereto.

30 The numeral 7 designates an inner elongated barrel smaller in diameter than socket 5 and having its upper portion extended into said socket 5, said barrel 7 having an upper enlarged head 8 spaced slightly from the inner wall of the socket, the head 8 having a beveled under edge 8' for a purpose presently seen.

35 A short outer barrel designated by reference character 9 surrounds the upper end of the inner barrel 7, in slightly spaced sliding relation thereto and is provided at its lower end with the pair of diametrically opposite and laterally projecting lugs 10—11 said barrel 9 being rotatable relative to barrel 7. At its upper end the outer barrel 9 is provided with an enlarged head 9' internally beveled as at 9'' to seat against the beveled under edge 8' of head 8. A sleeve 12 surrounding the inner barrel 7 below the barrel 9 and is provided with a pair of longitudinally extending slots 13 the sleeve 12 being adopted for telescoping of the lower end of the barrel 9

50 therein and the slots 13 to loosely receive the

lugs 10 and 11. A pair of diametrically opposite stop lugs one of which is shown at 13' extend upwardly from the upper end of the sleeve 12 at one edge of each slot 13 respectively. A suitable jamb nut 14 of the wedging type is interposed between the lower end of the socket structure 5 and the barrel 9 below the head 9' to secure the socket 5 to said barrel. The lower end of the sleeve 12 is externally threaded for attachment thereto of the internally threaded 10 downwardly tapering ring 15 against which the ribbed anchoring slips 16 are slidable, these slips being carried by the upper ends of the spring arms 17, which spring arms are secured at their lower ends as at 18 to the collar 18 slidable on the lower end of the inner barrel 7. A stop nut 20 is provided on the barrel 7 under the lower end of the sleeve 12 and a spring 21 is provided on the barrel 7 between the said nut 20 and the collar 18. The collar 18 carries the depending 20 hook member 22 which is engageable under the lateral pin 23 on the barrel 7.

A collar 24 is provided on the lower end portion of the inner barrel 7 and between the collars 18 and 24 are the bowed spring members 25 which serve to prevent rotation of the collars 18 and 24 and slips 16 in the well tubing (not shown).

Referring now to the use and operation of the invention, the described apparatus is lowered into the well casing, not shown, with the lower tubing section attached to the lower end of the inner barrel 7 and the upper tubing section attached to the nipple 6 and with the outer barrel 9 extended out of the upper end of the sleeve 12 with its lower end engaging said upper end of the barrel 9 and rotated relative thereto in a direction to engage the lugs 10 and 11 thereof with the lugs 13' of said outer barrel 9, such engagement of the lugs 10 and 11 with lugs 13' establishing the limits of rotation in that direction of said inner barrel 9. In the extended position of the outer barrel 9 the beveled end 9'' of the same and the beveled under edge 8' of head 8 seat one against the other, as shown in Fig. 2, whereby the tube line is open through the nipple 6 and inner barrel 7 only. Also preparatory to lowering the apparatus the collar 18 together with parts attached thereto are turned to the right as viewed in Fig. 1 to locate the hook member 22 under the pin 23 so that the ring 15 cannot be forced downwardly relative to the slips 16 sufficiently to spread the latter outwardly against the casing of the well. As the 55

apparatus is lowered into position the springs 25 grip the wall of the well casing, not shown, in the usual manner to center the lower section of well tubing therein as is usual. When the 5 apparatus is lowered sufficiently the upper section of well tubing is lifted slightly to thereby lift the socket 5 and the outer barrel 9 and inner barrel 7 in the collars 18 and 24 which are frictionally locked to the well casing by the 10 springs 25. Such lifting of the barrel 7 lifts the pin 23 out of the hook member 22 for subsequent rotation to clear the same. A slight rotary movement imparted in the proper direction to the upper tubing section rotates the 15 socket 5 together with the outer barrel 9 thus rotating the inner barrel 7 by frictional engagement between the upper end 9' of the latter with beveled edge 9" to rotate the pin 23 clear of said hook member 22. A slight downward 20 pressure on the upper tube section lowers the socket 5, outer barrel 7, and sleeve 12, the latter lowering ring 15 against the tension of the spring 21 to spread the slips 16 outwardly against the well casing and positively lock the 25 sleeve 12 thereto against movement.

The apparatus is now conditioned for operation to bleed the line as follows. The upper tubing section is rotated substantially a quarter turn in a direction to move the lugs 10 and 11 30 away from the lugs 13', said tubing, as will be understood, rotating socket 5 and outer barrel 9. At the end of approximately a quarter turn said lugs 10 and 11 register with the slots 13. At this point the upper tubing, socket 5 and 35 outer barrel 9 are lowered, the lugs 10 and 11 moving downwardly in said slots 13. This operation, as will be clear lowers the beveled end 9" of the outer barrel 9 from engagement with the beveled edge 8' of head 8 of inner barrel 7 40 thereby establishing communication between the upper tubing section and the slots 13 by way of the space between the socket 5 and the inner barrel 7 on the one hand, the space between the inner barrel and the outer one on the other 45 hand. Thus the line is bled by way of the slots 13.

The manner in which the apparatus is removed will, it is believed, be understood, the operations incident to such removal involving 50 merely reversal of those previously described.

While the foregoing specification sets forth the invention in specific terms, it is to be understood that numerous changes in the shape, size and materials may be resorted to without departing from the spirit and scope of the invention 55 as claimed hereinafter.

Having described the invention what is claimed as new is:—

1. A tubing bleeder for insertion into a well 60 casing to bleed well tubing therein comprising an elongated inner barrel having a lower end adapted for the attachment of a lower tubing section thereto and an upper enlarged head having an underbeveled edge providing a shoulder thereon, a sleeve surrounding said barrel in spaced relation thereto intermediate the ends thereof and having a pair of diametrically opposed bleeding slots therein extending inwardly from the upper end thereof for the escape of 65 fluid from the space between said inner barrel and sleeve, a short outer barrel surrounding 70

said inner barrel in spaced relation thereto and having an upper internally beveled end adapted to seat against said shoulder to form a seal preventing such escape of fluid through said slots, said outer barrel being endwise movable 5 into and out of said sleeve to unseat and seat said upper end thereof and rotatable in its seated position relative to said sleeve, said outer barrel having a pair of diametrically opposed lateral bosses on its lower end adapted under 10 rotation of said outer barrel to be registered with said slots for sliding into the same under inward movement of the outer barrel to lock said barrel and sleeve against relative rotation in the inwardly moved positions of said outer barrel, said 15 bosses in the seated position of said outer barrel being movable under rotation of said outer barrel onto the upper end of said sleeve to lock the outer barrel in seated position, and said bosses being engageable with said lugs to limit 20 such rotation of the outer barrel, means for attaching a tubing section to the upper end of said outer barrel in communication with said inner barrel and the space between said barrels, and means on the lower end of the inner barrel 25 to lock the same to the well casing against turning.

2. A tubing bleeder for insertion into a well casing to bleed well tubing therein comprising an elongated inner barrel having a lower end adapted for the attachment of a lower tubing section thereto and an upper enlarged head having an under-beveled edge providing a shoulder thereon, a sleeve surrounding said barrel in spaced relation thereto intermediate the ends thereof and having a pair of diametrically opposed bleeding slots therein extending inwardly from the upper end thereof for the escape of fluid from the space between said inner barrel and sleeve, a short outer barrel surrounding 40 said inner barrel in spaced relation thereto and having an upper internally beveled end adapted to seat against said shoulder to form a seal preventing such escape of fluid through said slots, said outer barrel being 45 endwise moveable into and out of said sleeve to unseat and seat said upper end thereof and rotatable in its seated position relative to said sleeve, said outer barrel having a pair of diametrically opposed lateral bosses on its lower 50 end adapted under rotation of said outer barrel to be registered with said slots for sliding into the same under inward movement of the outer barrel to lock said barrel and sleeve against relative rotation in the inwardly moved positions of 55 said outer barrel, said bosses in the seated position of said outer barrel being moveable under rotation of said outer barrel onto the upper end of said sleeve to lock the outer barrel in seated position, and said bosses being engageable with 60 said lugs to limit such rotation of the outer barrel, means for attaching a tubing section to the upper end of said outer barrel in communication with said inner barrel and the space between said barrels, and means on the lower end 65 of the inner barrel to lock the same to the well casing against turning, said attaching means including a socket telescoping over the upper ends of the inner and outer barrels in spaced relation to the former.

WILLIAM H. STIGALL.
